DISPLAY PANEL AND DISPLAY DEVICE

FIELD OF INVENTION

The present application is related to the field of display technology, and specifically, to a display panel and a display device.

BACKGROUND OF INVENTION

In order to achieve a narrow bezel design, a gate driving circuit is integrated into an array substrate in a display device of the prior art. Control of a pixel driving circuit is achieved by gate driver on array (GOA) technology integrated into the array substrate. However, with an increasing demand for high-resolution requirements of display devices, pixel sizes and spaces between scan lines are gradually reduced, and the number of required GOA units is gradually increased. In the prior art, sizes of GOA units are affected by thin-film transistors in the array substrate, so the sizes of the GOA cannot be less than or equal to 40 microns. Therefore, it is difficult to arrange a plurality of GOA units in a limited space.

SUMMARY OF INVENTION

The present application provides a display panel and a display device, which can improve a space limitation problem associated with arranging a plurality of gate driver on array (GOA) units in a display panel while the display panel achieves high resolution.

The present application provides a display panel including a non-display region and a GOA unit region in the non-display region. The GOA unit region includes multi-level GOA units arranged in multiple columns.

In an embodiment, the GOA unit region includes a first GOA unit region and a second GOA unit region. The multi-level GOA units in the first GOA unit region are odd-numbered GOA units. The multi-level GOA units in the second GOA unit region are even-numbered GOA units.

In an embodiment, the first GOA unit region includes n rows and m columns of the GOA units. A GOA unit at an i -th row and a j -th column is $G_{2m(i-1)+2j-1}$.

In an embodiment, the second GOA unit region includes x rows and y columns of the GOA units. A GOA unit at a z -th row and a w -th column is $G_{2y(z-1)+2w}$.

In an embodiment, the first GOA unit region includes n rows and m columns of the GOA units. A GOA unit at an i -th row and a j -th column is $G_{2m(i-1)+2j-1}$, and the GOA unit at a $(i+1)$ -th row and the j -th column is $G_{2m(i+1)-2j+1}$, wherein i is an odd number.

In an embodiment, the second GOA unit region includes x rows and y columns of the GOA units. A GOA unit at a z -th row and a w -th column is $G_{2y(z-1)+2w}$, and the GOA unit at a $(z+1)$ -th row and the w -th column is $G_{2y(z+1)-2w+2}$, wherein z is an odd number.

In an embodiment, the non-display region includes a first non-display region and a second non-display region, which are disposed on two opposite sides of a display region of the display panel. The first GOA unit region is positioned in the first non-display region. The second GOA unit region is positioned in the second non-display region.

In an embodiment, at least two columns of the GOA units are arranged symmetrically to each other.

In an embodiment, each of the GOA units includes an input end, an output end, and a pull-up module and a pull-down module connected to the input end. The pull-up

module is configured to control one of the GOA units to turn on in response to a turn-on signal received by the input end. The pull-down module is configured to control one of the GOA units to turn off in response to a turn-off signal received by the input end. The output end is configured to output a scan signal when one of the GOA units responses to the turn-on signal and a clock signal received by the input end.

In an embodiment, the GOA unit region includes P levels of the GOA units. A k -th level GOA unit is turned on in response to an output signal of a $(k-2)$ -th level GOA unit and is turned off in response to an output signal of a $(k+2)$ -th level GOA unit, and k is greater than 2.

In an embodiment, the first GOA unit region includes a first subregion and a second subregion. The first subregion includes $n1$ rows and $m1$ columns of GOA units. The second subregion includes an electrostatic discharge protective circuit and $n2$ rows and $m2$ columns of GOA units.

In an embodiment, a number of columns of the GOA units in the first subregion is greater than a number of columns of the GOA units in the second subregion.

In an embodiment, a difference between the number of columns of the GOA units in the first subregion and the number of columns of the GOA units in the second subregion is greater than or equal to 1.

In an embodiment, the second subregion includes at least four rows of the GOA units.

The present application further provides a display device including a display panel. The display panel includes a non-display region and a gate driver on array (GOA) unit region in the non-display region. The GOA unit region includes multi-level GOA units arranged in multiple columns.

In an embodiment, the GOA unit region includes a first GOA unit region and a second GOA unit region. The multi-level GOA units in the first GOA unit region are odd-numbered GOA units. The multi-level GOA units in the second GOA unit region are even-numbered GOA units.

In an embodiment, the first GOA unit region includes n rows and m columns of the GOA units. A GOA unit at an i -th row and a j -th column is $G_{2m(i-1)+2j-1}$.

In an embodiment, the second GOA unit region includes x rows and y columns of the GOA units. A GOA unit at a z -th row and a w -th column is $G_{2y(z-1)+2w}$.

In an embodiment, the first GOA unit region includes n rows and m columns of the GOA units. A GOA unit at an i -th row and a j -th column is $G_{2m(i-1)+2j-1}$, and the GOA unit at a $(i+1)$ -th row and the j -th column is $G_{2m(i+1)-2j+1}$, wherein i is an odd number.

In an embodiment, the second GOA unit region includes x rows and y columns of the GOA units. A GOA unit at a z -th row and a w -th column is $G_{2y(z-1)+2w}$, and the GOA unit at a $(z+1)$ -th row and the w -th column is $G_{2y(z+1)-2w+2}$, wherein z is an odd number.

Compared with the prior art, in the display panel and the display device provided by the present application, the display panel includes the non-display region and the GOA unit region in the non-display region, and the GOA unit region includes multi-level GOA units arranged in multiple columns. Therefore, the space limitation problem of arranging the plurality of GOA units in the display panel is improved while the display panel achieves high resolution.

DESCRIPTION OF DRAWINGS

FIGS. 1A and 1B are schematic structural diagrams of display panels according to embodiments provided by the present application.

FIGS. 2A to 2E are schematic structural diagrams of first gate driver on array (GOA) unit regions according to embodiments provided by the present application.

FIGS. 3A to 3D are schematic structural diagrams of second GOA unit regions according to embodiments provided by the present application.

DETAILED DESCRIPTION OF PREFERRED EMBODIMENTS

In order to make purposes, technical solutions, and effects of the present application clearer and more specific, the present application is further described in detail below with reference to the accompanying drawings and examples. It should be understood that the specific embodiments described herein are only used to explain the application, and are not used to limit the present application.

FIGS. 1A and 1B are schematic structural diagrams of display panels according to embodiments provided by the present application. FIGS. 2A to 2E are schematic structural diagrams of first gate driver on array (GOA) unit regions according to embodiments provided by the present application. FIGS. 3A to 3D are schematic structural diagrams of second GOA unit regions according to embodiments provided by the present application.

The present application provides a display panel including a non-display region 100a and a GOA unit region 101a in the non-display region 100a. The GOA unit region 101a includes multi-level GOA units 101 arranged in multiple columns, so that a plurality of GOA units 101 are distributed in the non-display region 100a with multiple columns. A space limitation problem of arranging the plurality of GOA units 101 in the display panel is improved while the display panel achieves high resolution.

Each of the GOA units 101 includes an input end, an output end, and a pull-up module and a pull-down module connected to the input end. The pull-up module is configured to control one of the GOA units 101 to turn on in response to a turn-on signal received by the input end. The pull-down module is configured to control one of the GOA units 101 to turn off in response to a turn-off signal received by the input end. The output end is configured to output a scan signal when one of the GOA units 101 responses to the turn-on signal and a clock signal received by the input end.

The output ends of the plurality of GOA units 101 are all connected to the scan lines in the display panel and are configured to transmit the scan signal to the display panel through the scan lines.

The turn-on signal includes a first turn-on signal STV and a second turn-on signal. The first turn-on signal STV is configured to turn on a first level GOA unit G_1 in the GOA units 101. Furthermore, the first turn-on signal STV is configured to turn on the first level GOA unit G_1 and a second level GOA unit G_2 in the GOA units 101. The second turn-on signal is configured to turn on the rest of the GOA units 101. The second turn-on signal can be transmitted individually or can be provided by the cascaded GOA units 101.

If the second turn-on signal is provided by the cascaded GOA units 101, the output end of a k-th level GOA unit G_k is connected to the input ends of subsequent q levels of the GOA units 101, so that a k-th level scan signal S_k output from the k-th level GOA unit G_k is used as a turn-on signal of the subsequent q levels of GOA units 101, thereby turning on the subsequent q level of the GOA units 101.

Furthermore, the k-th level GOA unit G_k can be connected to input ends of previous q levels of the GOA units 101, so

that the k-th level scan signal S_k output from the k-th level GOA unit G_k is used as the turn-off signal of the previous q levels of GOA units 101, thereby turning off the previous q level of the GOA units 101, wherein $q=\pm 1, \pm 2, \pm 3$, etc., q is determined as a positive integer to indicate that it is used in the subsequent q levels of the GOA units 101, and q is determined as a negative integer to indicate that it is used in the previous q levels of the GOA units 101.

Specifically, if $q=\pm 1$, the GOA unit region includes P levels of the GOA units 101. The first level GOA unit G_1 in the GOA units 101 is turned on in response to the first turn-on signal STV and output a first level scan signal S_1 ; the second level GOA unit G_2 in the GOA units 101 is turned on in response to the first level scan signal S_1 and output a second level scan signal S_2 ; the first level GOA unit G_1 is turned off in response to the second level scan signal S_2 ; and a third level GOA unit G_3 is turned on in response to the second level scan signal S_2 . Similarly, a k-th level GOA unit G_k is turned on in response to a $(k-1)$ -th level scan signal S_{k-1} output from a $(k-1)$ -th level GOA unit G_{k-1} and output a k-th level scan signal S_k , the $(k-1)$ -th level GOA unit G_{k-1} is turned off in response to the k-th level scan signal S_k output from the k-th level GOA unit G_k , a $(k+1)$ -th level GOA unit G_{k+1} is turned on in response to the k-th level scan signal S_k output from the k-th level GOA unit G_k and output a $(k+1)$ -th level scan signal S_{k+1} , and the k-th level GOA unit G_k is turned off in response to the $(k+1)$ -th level scan signal S_{k+1} output from the $(k+1)$ -th level GOA unit G_{k+1} . In this manner, the plurality of GOA units 101 of the GOA unit region complete a cycle of work until a P-th level GOA unit in the GOA units 101 is turned on and output a P-th level scan signal S_P . Because the first level GOA unit G_1 is turned on in response to the first turn-on signal STV, k is greater than 1 ($k>1$).

In FIGS. 2A to 2E and 3A to 3D, $q=\pm 2$ is taken as an example for description. Specifically, the GOA unit region includes P levels of the GOA units 101. The first level GOA unit G_1 and the second level GOA unit G_2 in the GOA units 101 are turned on in response to the first turn-on signal STV and respectively output a first level scan signal S_1 and a second level scan signal S_2 ; the third level GOA unit G_3 is turned on in response to the first level scan signal S_1 output from the first level GOA unit G_1 and output a third level scan signal S_3 ; the first level GOA unit G_1 is turned off in response to the third level scan signal S_3 ; and a fifth level GOA unit G_5 is turned on in response to the third level scan signal S_3 . Similarly, the k-th level GOA unit G_k is turned on in response to a $(k-2)$ -th level scan signal S_{k-2} output from a $(k-2)$ -th level GOA unit G_{k-2} and output the k-th level scan signal S_k , the $(k-2)$ -th level GOA unit G_{k-2} is turned off in response to the k-th level scan signal S_k output from the k-th level GOA unit G_k ; a $(k+2)$ -th level GOA unit G_{k+2} is turned on in response to the k-th level scan signal S_k output from the k-th level GOA unit G_k and output a $(k+2)$ -th level scan signal S_{k+2} ; and the k-th level GOA unit G_k is turned off in response to the $(k+2)$ -th level scan signal S_{k+2} output from the $(k+2)$ -th level GOA unit G_{k+2} . In this manner, the plurality of GOA units 101 of the GOA unit region complete a cycle of work until the P-th level GOA unit in the GOA units 101 is turned on and output the P-th level scan signal S_P . Because the first level GOA unit G_1 and the second level GOA unit G_2 are turned on in response to the first turn-on signal STV, k is greater than 2 ($k>2$).

Understandably, the plurality of GOA units are level-shifted from the first level to the P-th level, which means that after the first level GOA unit G_1 is turned on in response to the first turn-on signal STV; the second level GOA unit G_2

is turned on in response to the first turn-on signal STV; the third level GOA unit G_3 is turned on in response to the first level scan signal S_1 output from the first level GOA unit G_1 , a fourth level GOA unit G_4 is turned on in response to the second level scan signal S_2 output from the second level GOA unit G_2 ; and so on, until the P-th level GOA unit in the GOA units **101** is turned on in response to a (P-2)-th level scan signal S_{P-2} output from a (P-2)-th level GOA unit G_{P-2} and output the P-th level scan signal S_P .

The clock signal is transmitted to the GOA units **101** through a clock signal line connected to an input end of each of the GOA units **101**. Furthermore, the input end of each of the GOA units **101** is connected to a plurality of clock signal lines, and moreover, the input end of each of the GOA units **101** is connected to three clock signal lines.

Please refer to FIGS. **1B**, **2A** to **2E**, and **3A** to **3D**, the GOA unit region **101a** includes a first GOA unit region **102a** and a second GOA unit region **103a**. The multi-level GOA units **101** in the first GOA unit region **102a** are odd-numbered GOA units, and the multi-level GOA units **101** in the second GOA unit region **103a** are even-numbered GOA units. As a result, the plurality of GOA units **101** are evenly distributed in the first GOA unit region **102a** and the second GOA unit region **103a**.

In addition, when the display panel includes P levels of the GOA units **101**, the multi-level GOA units **101** positioned in the first GOA unit region **102a** can be a previous P/2 levels of the GOA units **101**, and the multi-level GOA units **101** positioned in the second GOA unit region **103a** can be a subsequent P/2 levels of the GOA units **101**. Compared with a configuration that the previous P/2 levels of the GOA units **101** are disposed in the first GOA unit region **102a**, a configuration, which disposed the multi-level odd-numbered GOA units in the first GOA unit region **102a** and disposed the multi-level even-numbered GOA units in the second GOA unit region **103a**, can reduce wiring lengths between the P/2 levels and the P/2+1 levels and reduce impedance of wirings.

Specifically, please refer to FIGS. **2A** to **2B**, the first GOA unit region **102a** includes n rows and m columns of the GOA units **101**. A GOA unit at an i-th row and a j-th column is $G_{2m(i-1)+2j-1}$, wherein $i=1, 2, 3, \dots, n$, $j=1, 2, 3, \dots, m$, $n>1$, and $m>1$. Specifically, if the display panel includes P levels of the GOA units **101**, $n=2, 3, 4, 5, \dots, P/4, \dots, P/2$, etc., and $m=2, 3, 4, 5, \dots, P/4, \dots, P/2$, etc.

In the first GOA unit region **102a**, $n \times m$ levels of the GOA units **101** are arranged in the following manner:

$$\begin{bmatrix} G_1 & G_3 & \dots & G_{2j-1} & \dots & G_{2m-1} \\ G_{2m+1} & G_{2m+3} & \dots & G_{2m+2j-1} & \dots & G_{4m-1} \\ G_{4m+1} & G_{4m+3} & \dots & G_{4m+2j-1} & \dots & G_{6m-1} \\ \vdots & \vdots & \vdots & \vdots & \vdots & \vdots \\ G_{2m(i-1)+1} & G_{2m(i-1)+3} & \dots & G_{2m(i-1)+2j-1} & \dots & G_{2mi-1} \\ \vdots & \vdots & \vdots & \vdots & \vdots & \vdots \\ G_{2m(n-1)+1} & G_{2m(n-1)+3} & \dots & G_{2m(n-1)+2j-1} & \dots & G_{2mn-1} \end{bmatrix}$$

Specifically, in the first GOA unit region **102a** as shown in FIGS. **2A** to **2B**, $m=2$ is taken as an example for description. In the plurality of GOA units **101**, the first level

GOA unit G_1 and the third level GOA unit G_3 are positioned in a first row, the fifth level GOA unit G_5 and a seventh level GOA G_7 are positioned in a second row. Similarly, a [4(n-1)+1]-th level GOA unit $G_{4(n-1)+1}$ and a [4(n-1)+3]-th level GOA unit $G_{4(n-1)+3}$ are positioned in an n-th row.

A first column (j=1) includes the first level GOA unit G_1 , the fifth level GOA unit $G_5, \dots, a [4(i-1)+1]-th level GOA unit $G_{4(i-1)+1}$ positioned in an i-th row, $\dots$, and the [4(n-1)+1]-th level GOA unit $G_{4(n-1)+1}$ positioned in the n-th row.$

A second column (j=2) includes the third level GOA unit G_3 , the seventh level GOA unit $G_7, \dots, a [4(i-1)+3]-th level GOA unit $G_{4(i-1)+3}$ positioned in the i-th row, $\dots$, and the [4(n-1)+3]-th level GOA unit $G_{4(n-1)+3}$ positioned in the n-th row.$

Furthermore, in the first GOA unit region **102a**, at least two columns of the GOA units **101** are arranged symmetrically to each other. Moreover, the clock signal lines for transmitting the clock signal are disposed between two columns of symmetrical GOA units **101**, so that the two columns of symmetrical GOA units **101** share the clock signal.

Specifically, please refer to FIG. **2B**, the plurality of GOA units **101** in the first column and the plurality of GOA units **101** in the second column are symmetrical. Clock signal lines OK_1, CK_3, CK_5 , and CK_7 are disposed between the two columns of symmetrical GOA units **101**. The input end of the first level GOA unit G_1 is connected to the clock lines CK_1, CK_3 , and CK_7 , the input end of the third level GOA unit G_3 is connected to the clock lines OK_1, CK_3 , and CK_5 ; the input end of the fifth level GOA unit G_5 is connected to the clock lines CK_3, CK_5 , and CK_7 ; and the input end of the seventh level GOA unit G_7 is connected to the clock lines CK_5, CK_7 , and OK_1 . Therefore, the first level GOA unit G_1 and the third level GOA unit G_3 share the clock signal lines CK_1 and CK_3 , the third level GOA unit G_3 and the fifth level GOA unit G_5 share the clock signal lines CK_3 and CK_5 ; the fifth level GOA unit G_5 and the seventh level GOA unit G_7 share the clock signal lines CK_5 and CK_7 , and the seventh level GOA unit G_7 and the first level GOA unit G_1 share the clock signal lines CK_7 and CK_1 . In this way, a wiring width of the clock signal lines in the GOA unit region **101a** is reduced, and a lateral width of the first GOA unit region **102a** is reduced.

A ninth level GOA unit and the first level GOA unit G_1 are connected to same clock signal lines; an eleventh level GOA unit and the third level GOA unit G_3 are connected to same clock signal lines; a thirteenth level GOA unit and the fifth level GOA unit G_5 are connected to same clock signal lines; and a fifteenth level GOA unit and the seventh level GOA unit G_7 are connected to same clock signal lines. In this manner, connection methods of other odd-numbered GOA units and the clock signal lines can be obtained.

Please continue to refer to FIGS. **2C** to **2D**, the first GOA unit region includes n rows and m columns of the GOA units. A GOA unit at the i-th row and the j-th column is $G_{2m(i-1)+2j-1}$, and the GOA unit at a (i+1)-th row and the j-th column is $G_{2m(i+1)-2j+1}$, wherein i is an odd number (i.e., $i=1, 3, 5, \dots, n$), $j=1, 2, 3, \dots, m$, $n>1$, and $m>1$. Specifically, when the display panel includes P levels of the GOA units **101**, $n=2, 3, 4, 5, 8, 10, 20, 50, 100, \dots, P/4, \dots, P/2$, etc., and $m=2, 3, 4, 5, \dots, P/4, \dots, P/2$, etc.

In the first GOA unit region **102a**, if n is an odd number, $n \times m$ levels of the GOA units **101** are arranged in the following manner:

G_1	G_3	$\dots$	G_{2j-1}	$\dots$	G_{2m-1}
G_{4m-1}	G_{4m-3}	$\dots$	$G_{4m-2j+1}$	$\dots$	G_{2m+1}
G_{4m+1}	G_{4m+3}	$\dots$	$G_{4m+2j-1}$	$\dots$	G_{6m-1}
$\vdots$	$\vdots$	$\vdots$	$\vdots$	$\vdots$	$\vdots$
$G_{2m(i-1)+1}$	$G_{2m(i-1)+3}$	$\dots$	$G_{2m(i-1)+2j-1}$	$\dots$	G_{2mi-1}
$G_{2m(i+1)-1}$	$G_{2m(i+1)-3}$	$\dots$	$G_{2m(i+1)-2j+1}$	$\dots$	G_{2mi+1}
$\vdots$	$\vdots$	$\vdots$	$\vdots$	$\vdots$	$\vdots$
$G_{2m(n-1)+1}$	$G_{2m(n-1)+3}$	$\dots$	$G_{2m(n-1)+2j-1}$	$\dots$	G_{2mn-1}

If n is an even number, $n \times m$ levels of the GOA units **101** are arranged in the following manner:

G_1	G_3	$\dots$	G_{2j-1}	$\dots$	G_{2m-1}
G_{4m-1}	G_{4m-3}	$\dots$	$G_{4m-2j+1}$	$\dots$	G_{2m+1}
G_{4m+1}	G_{4m+3}	$\dots$	$G_{4m+2j-1}$	$\dots$	G_{6m-1}
$\vdots$	$\vdots$	$\vdots$	$\vdots$	$\vdots$	$\vdots$
$G_{2m(i-1)+1}$	$G_{2m(i-1)+3}$	$\dots$	$G_{2m(i-1)+2j-1}$	$\dots$	G_{2mi-1}
$G_{2m(i+1)-1}$	$G_{2m(i+1)-3}$	$\dots$	$G_{2m(i+1)-2j+1}$	$\dots$	G_{2mi+1}
$\vdots$	$\vdots$	$\vdots$	$\vdots$	$\vdots$	$\vdots$
G_{2mn-1}	G_{2mn-3}	$\dots$	$G_{2mn-2j+1}$	$\dots$	$G_{2m(n-1)+1}$

Specifically, in the first GOA unit region **102a** as shown in FIGS. 2C to 2D, $m=3$ is taken as an example for description. In the plurality of GOA units **101**, the first level GOA unit G_1 , the third level GOA unit G_3 , and the fifth level GOA unit G_5 are positioned in the first row, and the eleventh level GOA unit G_{11} , the ninth level GOA unit G_9 , and the seventh level GOA unit G_7 are positioned in the second row. Similarly, if n is an odd number, a $[6(n-1)+1]$ -th level GOA unit $G_{6(n-1)+1}$, a $[6(n-1)+3]$ -th level GOA unit $G_{6(n-1)+3}$, and a $[6(n-1)+5]$ -th level GOA unit $G_{6(n-1)+5}$ are positioned in the n-th row. If n is an even number, a $(6n-1)$ -th level GOA unit G_{6n-1} , a $(6n-3)$ -th level GOA unit G_{6n-3} , and a $(6n-5)$ -th level GOA unit G_{6n-5} are positioned in the n-th row.

The first column ($j=1$) includes the first level GOA unit G_1 , the eleventh level GOA unit G_{11} , . . . , a $[6(i-1)+1]$ -th level GOA unit $G_{6(i-1)+1}$ positioned in the i-th row (odd-numbered row), a $[6(i+1)-1]$ -th level GOA unit $G_{6(i+1)-1}$ positioned in the $(i+1)$ -th row (even-numbered row, i.e., $i+1$ is an even number), . . . , and the $[6(n-1)+1]$ -th level GOA unit $G_{6(n-1)+1}$ positioned in the n-th row (n is an odd number); or the $(6n-1)$ -th level GOA unit G_{6n-1} positioned in the n-th row (n is an even number).

The second column ($j=2$) includes the third level GOA unit G_3 , the ninth level GOA unit G_9 , . . . , a $[6(i-1)+3]$ -th level GOA unit $G_{6(i-1)+3}$ positioned in the i-th row (odd-numbered row), a $[6(i+1)-3]$ -th level GOA unit $G_{6(i+1)-3}$ positioned in the $(i+1)$ -th row (even-numbered row), . . . , and the $[6(n-1)+3]$ -th level GOA unit $G_{6(n-1)+3}$ positioned in the n-th row (n is an odd number); or a $(6n-3)$ -th level GOA unit G_{6n-3} positioned in the n-th row (n is an even number).

A third column ($j=3$) includes the fifth level GOA unit G_5 , the seventh level GOA unit G_7 , . . . , a $[6(i-1)+5]$ -th level GOA unit $G_{6(i-1)+5}$ positioned in the i-th row (odd-numbered row), a $[6(i+1)-5]$ -th level GOA unit $G_{6(i+1)-5}$ positioned in the $(i+1)$ -th row (even-numbered row), . . . , and the $[6(n-1)+5]$ -th level GOA unit $G_{6(n-1)+5}$ positioned in the n-th row (n is an odd number); or a $(6n-5)$ -th level GOA unit G_{6n-5} positioned in the n-th row (n is an even number).

Furthermore, in the first GOA unit region **102a**, at least two columns of the GOA units **101** are arranged symmetrically to each other. Moreover, the clock signal lines for transmitting the clock signal are disposed between two columns of symmetrical GOA units **101**, so that the two columns of symmetrical GOA units **101** share the clock signal.

Specifically, please refer to FIG. 2D, the plurality of GOA units **101** in the first column and the plurality of GOA units **101** in the second column are symmetrical. The clock signal lines OK_1 , CK_3 , CK_5 , and CK_7 are disposed between the two columns of symmetrical GOA units **101**. The first level GOA unit G_1 and the third level GOA unit G_3 share the clock signal lines CK_1 and CK_3 , the first level GOA unit G_1 and the ninth level GOA unit G_9 share the clock signal lines CK_1 , CK_3 , and CK_7 , and the third level GOA unit G_3 and the eleventh level GOA unit G_{11} share the clock signal lines CK_1 , CK_3 , and CK_5 . In this way, the lateral width of the first GOA unit region **102a** is reduced.

In addition, the GOA units **101** in the odd-numbered rows can be obtained, which are arranged in reverse order of the GOA units **101** in the odd-numbered rows in FIGS. 2A to 2B, and the GOA units **101** in the even-numbered rows can be obtained, which are arranged in same order as the GOA units **101** in the even-numbered rows in FIGS. 2A to 2B. Otherwise, the GOA units **101** in the odd-numbered rows are arranged in reverse order, and the GOA units **101** in the even-numbered rows are arranged in reverse order of the GOA units **101** in the even-numbered rows in FIGS. 2A to 2B. Details are not described herein again.

Please continue to refer to FIG. 2E, the first GOA unit region **102a** includes a first subregion **1021a** and a second subregion **1022a**. The first subregion **1021a** includes n_1 rows and m_1 columns of GOA units. The second subregion **1022a** includes n_2 rows and m_2 columns of GOA units. A number of columns m_1 of the GOA units in the first subregion **1021a** is greater than a number of columns m_2 of the GOA units in the second subregion **1022a**, which means that $m_1 > m_2$. A sum of a number of rows n_1 of the GOA units in the first subregion **1021a** and a number of rows n_2 of the GOA units in the second subregion **1022a** is equal to a number of rows n of the GOA units in the first GOA unit region **102a**, which means that $n_1+n_2=n$. The second subregion **1022a** is provided with an electrostatic discharge protective circuit ESD. In this way, a lateral width of the display panel is reduced.

In order to ensure that the second subregion **1022a** has enough space to place the electrostatic discharge protective circuit ESD, a difference between the number of columns m_1 of the GOA units in the first subregion **1021a** and the number of columns m_2 of the GOA units in the second subregion **1022a** can be configured to be greater than or equal to 1. Furthermore, a difference between n and n_1 is greater than or equal to 4, which means that the second subregion **1022a** includes at least four rows of the GOA units.

The electrostatic discharge protective circuit ESD is connected to the input end of each of the GOA units **101** connected to the clock signal lines, so that the clock signal provided by the driving circuit can be transmitted to each of the GOA units **101**. The plurality of GOA units **101** in the first subregion **1021a** and the second subregion **1022a** can be arranged in the manner as shown in FIGS. 2A to 2B and/or 2C to 2D. Details are not described herein again.

Please continue to refer to FIGS. 3A to 3D, the second GOA unit region **103a** includes x rows and y columns of the GOA units **101**. A GOA unit at a z -th row and a w -th column

is $G_{2y(z-1)+2w}$, wherein $z=1, 2, 3, \dots, x$, $w=1, 2, 3, \dots, y$, $x>1$, and $y>1$. Specifically, when the display panel includes P levels of the GOA units **101**, $x=2, 3, 4, 5, 8, 10, 20, 50, 100, \dots, P/4, \dots, P/2$, etc., and $y=2, 3, 4, 5, \dots, P/4, \dots, P/2$, etc.

In the second GOA unit region **103a**, $x\times y$ levels of the GOA units **101** are arranged in the following manner:

$$\begin{bmatrix} G_2 & G_4 & \cdots & G_{2w} & \cdots & G_{2y} \\ G_{2y+2} & G_{2y+4} & \cdots & G_{2y+2w} & \cdots & G_{4y} \\ G_{4y+2} & G_{4y+4} & \cdots & G_{4y+2w} & \cdots & G_{6y} \\ \vdots & \vdots & \vdots & \vdots & \vdots & \vdots \\ G_{2y(z-1)+2} & G_{2y(z-1)+4} & \cdots & G_{2y(z-1)+2w} & \cdots & G_{2zy} \\ \vdots & \vdots & \vdots & \vdots & \vdots & \vdots \\ G_{2y(x-1)+2} & G_{2y(x-1)+4} & \cdots & G_{2y(x-1)+2w} & \cdots & G_{2xy} \end{bmatrix}$$

Specifically, in the second GOA unit region **103a** as shown in FIGS. 3A to 3B, $y=2$ is taken as an example for description. In the plurality of GOA units **101**, the second level GOA unit G_2 and the fourth level GOA unit G_4 are positioned in the first row, a sixth level GOA unit G_6 and a eighth level GOA G_8 are positioned in the second row. Similarly, a $[4(x-1)+2]$ -th level GOA unit $G_{4(x-1)+2}$ and a $[4(x-1)+4]$ -th level GOA unit $G_{4(x-1)+4}$ are positioned in an x -th row.

A first column ($w=1$) includes the second level GOA unit G_2 , the sixth level GOA unit $G_6, \dots, a [4(z-1)+2]$ -th level GOA unit $G_{4(z-1)+2}$ positioned in a z -th row, $\dots$, and the $[4(x-1)+2]$ -th level GOA unit $G_{4(x-1)+2}$ positioned in the x -th row.

A second column ($w=2$) includes the fourth level GOA unit G_4 , the eighth level GOA unit $G_8, \dots, a [4(z-1)+4]$ -th level GOA unit $G_{4(z-1)+4}$ positioned in the z -th row, $\dots$, and the $[4(x-1)+4]$ -th level GOA unit $G_{4(x-1)+4}$ positioned in the x -th row.

Furthermore, in the second GOA unit region **103a**, at least two columns of the GOA units **101** are arranged symmetrically to each other. Moreover, the clock signal lines for transmitting the clock signal are disposed between two columns of symmetrical GOA units **101**, so that the two columns of symmetrical GOA units **101** share the clock signal.

Specifically, please refer to FIG. 3B, the plurality of GOA units **101** in the first column and the plurality of GOA units **101** in the second column are symmetrical. Clock signal lines CK_2, CK_4, CK_6 , and CK_8 are disposed between the two columns of symmetrical GOA units **101**. The input end of the second level GOA unit G_2 is connected to the clock lines CK_2, CK_4 , and CK_8 , the input end of the fourth level GOA unit G_4 is connected to the clock lines CK_2, CK_4 , and CK_6 , the input end of the sixth level GOA unit G_6 is connected to the clock lines CK_4, CK_6 , and CK_8 , and the input end of the eighth level GOA unit G_8 is connected to the clock lines CK_6, CK_8 , and CK_2 . Therefore, the second level GOA unit G_2 and the fourth level GOA unit G_4 share the clock signal lines CK_2 and CK_4 , the fourth level GOA unit G_4 and the sixth level GOA unit G_6 share the clock signal lines CK_4 and CK_6 , the sixth level GOA unit G_6 and the eighth level GOA unit G_8 share the clock signal lines CK_6 and CK_8 , and the eighth level GOA unit G_8 and the second level GOA unit G_2 share the clock signal lines CK_8 and CK_2 . In this way, a wiring width of the clock signal lines in the second GOA unit region **103a** is reduced, and a lateral width of the second GOA unit region **103a** is reduced.

A tenth level GOA unit and the second level GOA unit G_2 are connected to same clock signal lines; a twelfth level GOA unit and the fourth level GOA unit G_4 are connected to same clock signal lines; a fourteenth level GOA unit and the sixth level GOA unit G_6 are connected to same clock signal lines; and a sixteenth level GOA unit and the eighth level GOA unit G_8 are connected to same clock signal lines. In this manner, connection methods of other even-numbered GOA units and the clock signal lines can be obtained.

10 Please continue to refer to FIGS. 3C to 3D, the second GOA unit region includes x rows and y columns of the GOA units. A GOA unit at the z -th row and the w -th column is $G_{2y(z-1)+2w}$, and the GOA unit at a $(z+1)$ -th row and the w -th column is $G_{2y(z+1)-2w+2}$, wherein z is an odd number (i.e., $z=1, 3, 5, \dots$, and x), $w=1, 2, 3, \dots, y$, $x>1$, and $y>1$. Specifically, when the display panel includes P levels of the GOA units **101**, $x=2, 3, 4, 5, 8, 10, 20, 50, 100, \dots, P/4, \dots, P/2$, etc.

15 In the second GOA unit region **103a**, if x is an odd number, $x\times y$ levels of the GOA units **101** are arranged in the following manner:

$$\begin{bmatrix} G_2 & G_4 & \cdots & G_{2w} & \cdots & G_{2y} \\ G_{4y} & G_{4y-2} & \cdots & G_{4y-2w+2} & \cdots & G_{2y+2} \\ G_{4y+2} & G_{4y+4} & \cdots & G_{4y+2w} & \cdots & G_{6y} \\ \vdots & \vdots & \vdots & \vdots & \vdots & \vdots \\ G_{2y(z-1)+2} & G_{2y(z-1)+4} & \cdots & G_{2y(z-1)+2w} & \cdots & G_{2zy} \\ G_{2y(z+1)} & G_{2y(z+1)-2} & \cdots & G_{2y(z+1)-2w+2} & \cdots & G_{2zy+2} \\ \vdots & \vdots & \vdots & \vdots & \vdots & \vdots \\ G_{2y(x-1)+2} & G_{2y(x-1)+4} & \cdots & G_{2y(x-1)+2w} & \cdots & G_{2xy} \end{bmatrix}$$

25 If x is an even number, $x\times y$ levels of the GOA units **101** are arranged in the following manner:

$$\begin{bmatrix} G_2 & G_4 & \cdots & G_{2w} & \cdots & G_{2y} \\ G_{4y} & G_{4y-2} & \cdots & G_{4y-2w+2} & \cdots & G_{2y+2} \\ G_{4y+2} & G_{4y+4} & \cdots & G_{4y+2w} & \cdots & G_{6y} \\ \vdots & \vdots & \vdots & \vdots & \vdots & \vdots \\ G_{2y(z-1)+2} & G_{2y(z-1)+4} & \cdots & G_{2y(z-1)+2w} & \cdots & G_{2zy} \\ G_{2y(z+1)} & G_{2y(z+1)-2} & \cdots & G_{2y(z+1)-2w+2} & \cdots & G_{2zy+2} \\ \vdots & \vdots & \vdots & \vdots & \vdots & \vdots \\ G_{2xy} & G_{2xy-2} & \cdots & G_{2xy-2w+2} & \cdots & G_{2y(x-1)+2} \end{bmatrix}$$

30 Specifically, in the second GOA unit region **103a** as shown in FIGS. 3C to 3D, $m=3$ is taken as an example for description. In the plurality of GOA units **101**, the second level GOA unit G_2 , the fourth level GOA unit G_4 , and the sixth level GOA unit G_6 are positioned in the first row; the twelfth level GOA unit G_{12} , the tenth level GOA unit G_{10} , and the eighth level GOA G_8 are positioned in the second row. Similarly, if x is an odd number, a $[6(x-1)+2]$ -th level GOA unit $G_{6(x-1)+2}$, a $[6(x-1)+4]$ -th level GOA unit $G_{6(x-1)+4}$, and a $[6(x-1)+6]$ -th level GOA unit $G_{6(x-1)+6}$ are positioned in the x -th row. If x is an even number, a $6x$ -th level GOA unit G_{6x} , a $(6x-2)$ -th level GOA unit G_{6x-2} , and a $(6x-4)$ -th level GOA unit G_{6x-4} are positioned in the x -th row.

35 The first column ($w=1$) includes the second level GOA unit G_2 , the twelfth level GOA unit $G_{12}, \dots, a [6(z-1)+2]$ -th level GOA unit $G_{6(z-1)+2}$ positioned in the z -th row (odd-numbered row), a $6(z+1)$ -th level GOA unit $G_{6(z+1)}$ positioned in the $(z+1)$ -th row (even-numbered row, i.e., $z+1$ is an even number), $\dots$, and the $[6(x-1)+2]$ -th level GOA unit

11

$G_{6(x-1)+2}$ positioned in the x-th row (x is an odd number); or the 6x-th level GOA unit G_{6x} positioned in the x-th row (x is an even number).

The second column (w=2) includes the fourth level GOA unit G_4 , the tenth level GOA unit G_{10} , . . . , a [6(z-1)+4]-th level GOA unit $G_{6(z-1)+4}$ positioned in the z-th row (odd-numbered row), a [6(z+1)-2]-th level GOA unit $G_{6(z+1)-2}$ positioned in the (z+1)-th row (even-numbered row), . . . , and the [6(x-1)+4]-th level GOA unit $G_{6(x-1)+4}$ positioned in the x-th row (x is an odd number); or a (6x-2)-th level GOA unit G_{6x-2} positioned in the x-th row (x is an even number).

A third column (w=3) includes the sixth level GOA unit G_6 , the eighth level GOA unit G_8 , . . . , a [6(z-1)+6]-th level GOA unit $G_{6(z-1)+6}$ positioned in the z-th row (odd-numbered row), a [6(z+1)-4]-th level GOA unit $G_{6(z+1)-4}$ positioned in the (z+1)-th row (even-numbered row), . . . , and the [6(x-1)+6]-th level GOA unit $G_{6(x-1)+6}$ positioned in the x-th row (x is an odd number); or a (6x-4)-th level GOA unit G_{6x-4} positioned in the x-th row (x is an even number).

Please continue to refer to FIG. 3D, the plurality of GOA units **101** in the first column and the plurality of GOA units **101** in the second column are symmetrical. The clock signal lines CK_2 , CK_4 , CK_6 , and CK_8 are disposed between the two columns of symmetrical GOA units **101**. The second level GOA unit G_2 and the fourth level GOA unit G_4 share the clock signal lines CK_2 and CK_4 , the second level GOA unit G_2 and the tenth level GOA unit G_{10} share the clock signal lines CK_2 , CK_4 , and CK_8 , and the fourth level GOA unit G_4 and the twelfth level GOA unit G_{12} share the clock signal lines CK_2 , CK_4 , and CK_6 . In this way, the lateral width of the second GOA unit region **103a** is reduced.

Furthermore, the second GOA unit region **103a** includes a third subregion and a fourth subregion. The third subregion includes x_1 rows and y_1 columns of GOA units, and the fourth subregion includes x_2 rows and y_2 columns of GOA units, wherein $y_1 > y_2$, and $x_1+x_2=x$. The fourth subregion is provided with the electrostatic discharge protective circuit ESD. In this way, the lateral width of the display panel is reduced.

In addition, the GOA units **101** in the odd-numbered rows can be obtained, which are arranged in reverse order of the GOA units **101** in the odd-numbered rows in FIGS. 3A to 3B, and the GOA units **101** in the even-numbered rows can be obtained, which are arranged in same order as the GOA units **101** in the even-numbered rows in FIGS. 3A to 3B. Otherwise, the GOA units **101** in the odd-numbered rows are arranged in reverse order, and the GOA units **101** in the even-numbered rows are arranged in reverse order of the GOA units **101** in the even-numbered rows in FIGS. 3A to 3B. Details are not described herein again.

Please continue to refer to FIGS. 2A to 2E and 3A to 3D, when the display panel includes P levels of the GOA units **101**, a sum of $n \times m$ levels of the GOA units **101** and $x \times y$ levels of the GOA units **101** is equal to P. n and x can be equal or unequal, and m and y can be equal or unequal.

Please continue to refer to FIG. 1B, the non-display region **100a** includes a first non-display region **100c** and a second non-display region **100d**, which are disposed on two opposite sides of a display region **100b** of the display panel. The first GOA unit region **102a** is positioned in the first non-display region **100c**, and the second GOA unit region **103a** is positioned in the second non-display region **100d**.

In addition, odd-numbered GOA units and even-numbered GOA units can also be arranged sequentially, and meanwhile, the GOA unit region **101a** is only positioned on one side of the display panel. As shown in FIG. 1A, the GOA unit region **101a** includes R rows and T columns of the GOA

12

units. A GOA unit at a r-th row and a t-th column is $G_{T(r-1)+t}$, wherein r=1, 2, 3, . . . , R, t=1, 2, 3, . . . , T, R>1, and T>1.

The multi-level GOA units **101** can be arranged in accordance with other manners in addition to arrangements shown in FIGS. 2A to 2E and 3A to 3D. Once the multi-level GOA units are ensured to be arranged in multiple columns in the GOA unit region **101a**, the space limitation problem associated with arranging the plurality of GOA units **101** in the display panel is improved while the display panel achieves high resolution.

The present application further provides a display device including the display panel described above. The display device includes a liquid crystal display device, a flexible display device, etc. The flexible display device includes a light-emitting device. The light-emitting device includes at least one of an organic light-emitting diode, a micro light-emitting diode, or a sub-millimeter light-emitting diode.

Furthermore, the display device includes a virtual reality display device, a projector, a mobile phone, a bracelet, a computer, and other devices.

The present application provides the display panel and the display device. the display panel includes the non-display region **100a** and the GOA unit region **101a** in the non-display region **100a**. The GOA unit region **101a** includes multi-level GOA units **101** arranged in multiple columns. Therefore, the space limitation problem associated with arranging the plurality of GOA units in the display panel is improved while the display panel achieves high resolution.

In the above embodiments, the descriptions of the various embodiments are different in emphases, for contents not described in detail, please refer to related description of other embodiments. The description of embodiments above is only for helping to understand technical solutions of the present application and its core idea. Understandably, for a person of ordinary skill in the art can make various modifications of the technical solutions of the embodiments of the present application above. However, it does not depart from the scope of the technical solutions of the embodiments of the present application.

What is claimed is:

1. A display panel, comprising a display region and a non-display region disposed at a periphery of the display region, a gate driver on array (GOA) unit region being disposed in the non-display region,

wherein multi-level cascaded GOA units are arranged in the GOA unit region, the GOA unit region comprises a first GOA unit region and a second GOA unit region, and odd-numbered GOA units of the multi-level cascaded GOA units are arranged in the first GOA unit region and are arranged in n rows and m columns, and n>1, and m>1,

even-numbered GOA units of the multi-level cascaded GOA units are arranged in the second GOA unit region and are arranged in x rows and y columns, x>1 and y>1, wherein the first GOA unit region comprises a first subregion and a second subregion, and wherein n1 rows

and m1 columns of the odd-numbered GOA units are arranged in the first subregion, an electrostatic discharge protective circuit and n2 rows and m2 columns of the odd-numbered GOA units are arranged in the second subregion, the electrostatic discharge protective circuit is connected to each of the multi-level cascaded GOA units, and n1>1, m1>1, n2>1 and m2>1.

2. The display panel according to claim 1, wherein a GOA unit at an i-th row and a j-th column in the first GOA unit region is $G_{2m(i-1)+2j-1}$.

13

3. The display panel according to claim 1, wherein a GOA unit at a z-th row and a w-th column in the second GOA unit region is $G_{2y(z-1)+2w}$.
4. The display panel according to claim 1, wherein a GOA unit at an i-th row and a j-th column in the first GOA unit region is $G_{2m(i-1)+2j-1}$, and a GOA unit at a (i+1)-th row and the j-th column in the first GOA unit region is $G_{2m(i+1)-2j+1}$, wherein i is an odd number. 5
5. The display panel according to claim 1, wherein a GOA unit at a z-th row and a w-th column in the second GOA unit region is $G_{2y(z-1)+2w}$, and a GOA unit at a (z+1)-th row and the w-th column in the second GOA unit region is $G_{2y(z+1)-2w+2}$, wherein z is an odd number. 10
6. The display panel according to claim 1, wherein the non-display region comprises a first non-display region and a second non-display region, which are disposed on two opposite sides of a display region of the display panel; and the first GOA unit region is positioned in the first non- 15 display region, and the second GOA unit region is positioned in the second non-display region.
7. The display panel according to claim 1, wherein at least two columns of the multi-level cascaded GOA units are arranged symmetrically to each other. 20
8. The display panel according to claim 1, wherein in the GOA unit region, 25 a k-th level GOA unit is turned on in response to an output signal of a (k-2)-th level GOA unit and is turned off in response to an output signal of a (k+2)-th level GOA unit, and k is greater than 2.
9. The display panel according to claim 1, wherein a number of columns of the GOA units in the first subregion is greater than a number of columns of the GOA units in the second subregion. 30
10. The display panel according to claim 9, wherein a difference between the number of columns of the GOA units in the first subregion and the number of columns of the GOA units in the second subregion is greater than or equal to 1. 35
11. The display panel according to claim 1, wherein the second subregion comprises at least four rows of the GOA units. 40

14

12. A display device, comprising a display panel, wherein the display panel comprises a display region and a non-display region disposed at a periphery of the display region, a gate driver on array (GOA) unit region being disposed in the non-display region, and wherein multi-level cascaded GOA units are arranged in the GOA unit region, the GOA unit region comprises a first GOA unit region and a second GOA unit region, and odd-numbered GOA units of the multi-level cascaded GOA units are arranged in the first GOA unit region and are arranged in n rows and m columns, and n>1, and m>1, 10 even-numbered GOA units of the multi-level cascaded GOA units are arranged in the second GOA unit region and are arranged in x rows and y columns, and y>1, wherein the first GOA unit region comprises a first subregion a second subregion, and wherein n1 rows m1 columns of the odd-numbered GOA units are arranged in the first subregion, an electrostatic discharge protective circuit and n2 rows and m2 columns of the odd-numbered GOA units are arranged in the second subregion, the electrostatic discharge protective circuit is connected to each of the multi-level cascaded GOA units, and n1>1, m1>1, n2>1 and m2>1.
13. The display device according to claim 12, wherein a GOA unit at an i-th row and a j-th column in the first GOA unit region is $G_{2m(i-1)+2j-1}$. 15
14. The display device according to claim 12, wherein a GOA unit at a z-th row and a w-th column in the second GOA unit region is $G_{2y(z-1)+2w}$. 20
15. The display device according to claim 12, wherein a GOA unit at an i-th row and a j-th column in the first GOA unit region is $G_{2m(i-1)+2j-1}$, and a GOA unit at a (i+1)-th row and the j-th column in the first GOA unit region is $G_{2m(i+1)-2j+1}$, wherein i is an odd number. 25
16. The display device according to claim 12, wherein a GOA unit at a z-th row and a w-th column in the second GOA unit region is $G_{2y(z-1)+2w}$, and a GOA unit at a (z+1)-th row and the w-th column in the second GOA unit region is $G_{2y(z+1)-2w+2}$, wherein z is an odd number. 30
